UNITED STATES PATENT OFFICE.

BOHN CHAPIN HICKS, OF MINNEAPOLIS, MINNESOTA.

STOCK-CAR.

SPECIFICATION forming part of Letters Patent No. 338,743, dated March 30, 1886.

Application filed December 21, 1885. Serial No. 186,401. (No model.)

To all whom it may concern:

Be it known that I, BOHN CHAPIN HICKS, a citizen of the United States, a resident of Minneapolis, in the county of Hennepin and State of Minnesota, have invented certain new and useful Improvements in Stock-Cars, of which the following is a specification.

Figure 1 is a cross sectional view. Fig. 2 is a longitudinal sectional view of a portion of one end of a car, and Fig. 3 is a plan view in section of a portion of the parts shown in Fig. 2. Figs. 4 and 5 are enlarged perspective views of two modifications of the systems of cables used for operating the stall-bars. Fig. 6 represents the drums and sheaves as used in connection with the system shown in Fig. 4, and Fig. 7 represents the drums and sheaves as used in connection with the system shown in Fig. 5. Fig. 8 represents an enlarged de-

tail illustrating one method of attaching the stall-bars to the cable.

A' represents the floor; A², the roof, and A³ the stanchions or side frame-work connecting the roof and floor. The stanchions are shown arranged in pairs at equal distances apart along the sides of the car opposite each other. In a full-sized car the stanchions of each pair will be set about six inches apart, and with a space of about three feet from center to center of each pair of stanchions, the six-inch spaces adapted to support guides a for the ends of the stall-bars B, and the three-foot spaces representing the stalls for the animals. Journaled across the car, above each pair of the stanchions A³, is a shaft, b, carrying on each end above the spaces between the stanchions two drums, d' d'', fast to the shaft, and with a grooved sheave or pulley, d³, loose upon the shaft between each pair of drums. Attached to the floor A', in the bottom of the space between each pair of the stanchions A³, is a small pulley or sheave, d⁴, and pivoted in any suitable manner to the main roof plate A⁴, near the upper ends of each pair of stanchions A³, is another small sheave or pulley, d⁵. Each of the stanchions and stalls for the animals will thus be supplied with its own shaft b, set of drums d' d'', and sheaves d³, d⁴, and d⁵, as shown. An ordinary stock-car will be long enough to hold about ten of these sets of the stalls, five on each side of the doorway; but in the drawings I have shown only three complete stalls,

as being sufficient to illustrate the invention. On one end of each of the shafts b, outside the car, is attached a hand-wheel, e', and ratchet e'', by which the shaft may be revolved, and held at any point desired. A small wire cable will be attached at g' to each of the drums d', and carried thence down around the sheave d³, and thence upward over the sheave d⁴, and thence horizontally and around the sheave d⁵, and thence back horizontally to the drum d', around which it is wound a certain number of times, and connected by its end to the drum d'. The diameters and lengths of the drums d' d'' must so correspond to the height of the car or the distance which it is necessary to elevate the stall-bars B that they will each hold a sufficient quantity of the wire cable to reach from the drums to the floor A', as hereinafter explained.

If the distance from the floor A' to the roof-plate A⁴ be six feet, then each drum must be large enough to hold six feet of cable. A drum four inches in diameter will require to be 75 long enough to hold six coils of the cable, and when a cable one-fourth of an inch in diameter is used, the drums would require to be one and one half inch long. For convenience of future reference, I have designated the different parts of the cable by letters of reference, as follows: The part running from the drum d' to the sheave d³ is marked g², the part from the sheave d³ to the sheave d⁴ is marked g³, the part from the sheave d⁴ to the sheave d⁵ is 85 marked g⁴, and the part from the sheave d⁵ to the drum d' is marked g⁵.

The ends of the stall bars B are shown connected to the part g² of the cable in Fig. 1, and on the right and left hand stall in Fig. 2, while on the central stall in Figs. 2 and 3 the stall-bars are shown attached to an auxiliary section of cable, g⁶, the latter attached by its ends at g⁷ and g⁸ to the parts g² and g⁵ of the main cable. The operation and results produced are the 95 same, however, in both arrangements, as I shall show hereinafter.

As before stated, the stanchions A³ are provided with guide-plates a, between which the ends of the stall-bars B run. By this means 100 the parts g² g³ g⁶ and the sheaves d³ are protected, and are not liable to be injured or displaced by the animals.

The stall-bars B being in their downward

position, as in Fig. 1, and at the left of Fig. 2, by turning the shaft *b* to the left the cable will be wound upon the drum *d'* and unwound from the drum *d²*, and thus cause the parts *g³* (to 5 which the bars *B* are attached) to move upward over the sheaves *d³*, and thence horizontally along toward the sheaves *d⁵*, and thence around the sheaves *d⁵* in a horizontal line back toward the drums again, and carrying the 10 stall-bars with them and folding them out of the way. Then, when it is required to run the stall-bars down again, the shaft *b* will be revolved in the opposite direction.

In the modification shown in Fig. 5, and at 15 the center of Fig. 2, the action is the same, except that the bars *B* are attached to an auxiliary section of cable, *g⁶*, instead of the part *g³* of the main cable. By this arrangement the draft of the cable is positive, as both ends are 20 fast to the drums *d' d²*, and no slipping of the cable is possible under any circumstances.

Comparatively small cables can be used, as the strains upon them are not severe.

The stall-bars *B* may be connected to the 25 cables in any desired manner; but for the purpose of illustration I have shown in Fig. 8 one method of attachment which will answer the purpose, consisting in simple clamps *m*,

which connect the cables to the centers only of the stall-bars, and thus do not interfere with 30 their running around the sheaves or drums.

Having thus described my invention, what I claim as new is—

In a stock-car, a series of shafts, *b*, journaled across the upper part of the interior of said car at suitable intervals, and each of said shafts provided with two drums, *d' d²*, attached thereto, and one sheave, *d³*, loose thereon, sheave *d⁴*, attached to the floor of said car beneath each pair of said drums, a sheave, *d⁵*, journaled to 35 the upper part of the interior of said car, a cable attached by its ends to said drums *d' d²* and running around said sheaves, and a series of stall-bars, *B*, attached by their ends to each opposite pair of said cables, and means for revolving said shafts *b*, whereby said stall-bars will be elevated and depressed to form stalls 40 for the animals in said car.

In testimony whereof I have hereunto set my hand in the presence of two subscribing witnesses. 45

BOHN CHAPIN HICKS.
